UNITED STATES PATENT OFFICE.

WILLIAM H. STORER, OF CASPER, WYOMING.

BREECH-CLOSING AND GUN-FIRING MECHANISM.

Application filed April 5, 1924. Serial No. 704,475.

To all whom it may concern:

Be it known that I, WILLIAM H. STORER, a citizen of the United States, residing at Casper, in the county of Natrona and State of Wyoming, have invented certain new and useful Improvements in Breech-Closing and Gun-Firing Mechanism, of which the following is a specification.

This invention relates to breech closing and firing mechanisms for application upon gun structures in which ammunition in cartridge form is used and it consists in the novel features hereinafter described and claimed.

15 An object of the invention is to provide a mechanism of the character stated which includes a breech closing bolt adapted to connect with the barrel by means of an interrupted thread, there being means for throwing the bolt longitudinally and means simultaneously operated for turning the bolt in order to connect and disconnect the thread sections which are provided for locking the bolt in the breech of the barrel.

25 A further object of the invention is to provide in mechanisms of the character stated, a lever which is used for throwing the bolt and which is connected with or carries the means for turning the bolt, the said lever also serving as a trigger guard.

30 A further object of the invention is to provide in mechanisms of the character stated, means and features for swinging the hammer of the gun to cocked position when the bolt is disconnected from the barrel and is moved to a position to provide clearance space for a used shell to be ejected from the gun, through which clearance space a loaded shell may be inserted in the shell chamber at the breech of the barrel.

35 A still further object of the invention is to provide in mechanisms of the character stated, means which will serve as a barrier and prevent the hammer from striking the firing pin of the mechanism until such time, and until the arrangement of the parts is such that the breech closing bolt is properly and securely engaged in the breech of the barrel.

40 In the accompanying drawings:

Figure 1 is a sectional view of the breech mechanism showing the breech bolt in engagement with the breech of the barrel.

45 Figure 2 is a similar view showing the relative positions of the parts when the

breech closing bolt is disconnected from the breech of the barrel.

Figure 3 is a transverse sectional view of the mechanism cut on the line 3—3 of Figure 1.

Figure 4 is a longitudinal detail sectional view of the breech closing bolt used in the mechanism.

Figure 5 is an end view of the breech closing bolt.

Figure 6 is an end view of the breech closing bolt with a collar and links mounted thereon.

Figure 7 is a side view of a guide member used in the mechanism for directing the movement of the breech closing bolt.

The barrel of the gun is shown at 1 and the said barrel is provided at its inner end with the usual cartridge chamber 2 and breech opening 3. The inner surface of the opening 3 is provided with interrupted thread sections 4 of usual form. A stock 5 is connected with the inner end of the barrel 1 in a usual manner and is provided with a chamber 6. The stock 5 carries the usual hammer 7 and trigger 8.

A plate 9 is pivoted at its forward end to the forward portion of the stock 5 and is adapted to close within the lower portion of the chamber 6. Guide flanges 10 are provided at the side walls of the chamber 6 and in the vicinity of the upper edge thereof. A guide member 11 is provided at its sides with grooves 12 which receive the flanges 10 and the member 11 may slide along the flanges 10. A lever 13 is pivoted at one end to the guide member 11 and is provided at an intermediate portion with a slot 14 which receives a transversely disposed pin or stud 15 carried at the free end portion of the plate 9. The lever 13 is provided with a curved section 16 adapted to extend around the trigger 8 when the lever is swung to the position as shown in Figure 1. Therefore the said lever serves as a guard for the trigger 8. The lever 13 is further provided with a hand grip 17 which is adapted to bear against the under side of the intermediate portion of the stock 5 when the parts are in the position as shown in Figure 1.

The breech closing mechanism includes a bolt 18 which is provided at its inner end with interrupted thread sections 19 adapted to engage with the thread sections 4 of the breech opening 3 hereinbefore described.

The bolt 18 is provided at points between its ends with spaced collars 20 and the guide member 11 is received between the said collars 20. The bolt 17 is journalled for turning movement in the guide member 11. The bolt 18 is provided at its side with a longitudinally disposed key groove 21. A collar 22 is slidably mounted upon the bolt 18 and is provided with a tongue 23 which is received within the groove 21. A link 24 is pivoted at one end to the side of the collar 22 and pivoted at its other end to the free end portion of the plate 9. The bolt 18 is moved longitudinally and turned into engagement with the thread sections 4 of the breech opening 3 in the following manner. Assuming that the parts are in the positions as shown in Figure 2 of the drawings, the outer end of the lever 13 is swung toward the intermediate portion of the stock 5 whereby the section 16 is disposed around the trigger 8 and the grip 17 is moved into engagement with the gun stock. During such movement, the slot 14 moves along the pin 15 and the plate 9 is swung to the open position shown in Figure 2 to the closed position as shown in Figure 1, with relation to the chamber 6. At the same time, the guide member 11 is moved along the guide flanges 10 toward the breech opening 3, carrying with it the bolt 18. The longitudinal movement of the bolt 18 takes place initially owing to the lost motion provided by the slot and pin connection between the lever 13 and the plate 9. When the end of the bolt 18 arrives at the edge of the breech opening 3, the pin 15 has arrived at the end of the slot 14 and consequently as the bolt 18 is projected into the breech opening 3, the plate 9 is swung from the open position to the closed position. This movement on the part of the plate 9 moves the link 24 longitudinally whereby the collar 22 partially rotates the bolt 18 and the threads 19 thereof engage in the threads 4 at the inner surface of the breech opening 3. Thus the breech opening is closed by the bolt and the bolt is effectually locked in the said breech opening.

When the grip portion 17 of the lever 13 is swung away from the intermediate portion of the stock 5, the plate 9 is swung outwardly whereby the link 24 is pulled down and the bolt 18 is partially rotated and the threads 19 of the bolt are disengaged from the threads 4 in the breech opening 3. As the end portion 17 of the lever 13 continues to move away from the intermediate portion of the stock 5, the guide member 11 moves along the flanges 10 and the bolt 18 is moved to the position as shown in Figure 2 of the drawing. The striking end of the hammer 7 is located in the path of movement of the outer end of the bolt 18,

therefore the outer end of the bolt 18 engages the striking end or surface of the hammer 7 and swings the hammer from the position shown in Figure 1 to the cocked position as shown in Figure 2.

A spring hook 25 is mounted at the inner end of the bolt 18 and is adopted to engage over the flange of the cartridge (not shown), which is withdrawn from the chamber 2, and thus as the bolt 18 is moved away from the breech opening 3, an empty cartridge shell is extracted from the chamber 2 and passed into the chamber 6. A firing pin 26 is slidably mounted at the center of the bolt 18 and spaced collars 27 are carried by the said pin. A lug screw 28 passes through the side of the bolt 18 and its inner end is received between the collars 17 and the said lug screw serves as means for limiting the sliding movement of the firing pin in the said bolt. The bolt 18 is provided at its outer end with a transversely disposed shoulder 29 which lies just beyond the side of the path of movement of the hammer 7 when the inner end of the bolt 18 is in proper engagement with the threads 4 at the breech opening. The transverse breadth of the shoulder is such that the hammer 7 is prevented from striking the outer end of the pin 26 unless the edge of the shoulder is properly positioned with relation to the path of movement of the hammer and consequently it is impossible for the hammer to strike the outer end of the pin 26 until such time as the inner end of the bolt 18 is properly engaged with the inner end of the barrel 1 and the chamber 2 is securely closed. The bolt 18 is further provided at its outer end with an inclined or cam surface 31 which is adapted to move over the edge of the hammer 6 when the bolt 18 is moved to the position as shown in Figure 2 and starts the swinging of the hammer 7 from the pin engaging position to the cocked position as shown in Figure 2.

Having described the invention, what is claimed is:

A gun breech closing mechanism comprising a bolt mounted for longitudinal movement in alignment with the breech opening, means carried by the bolt for engaging in the walls of the breech opening when the bolt is turned, a plate pivotally mounted adjacent the breech opening, a lever fulcrumed upon the plate and having pin and slot connection therewith, a guide member pivoted to the lever and loosely mounted upon the bolt, means for directing the guide member toward and away from the breech opening, and means connected with the bolt and the plate for turning the bolt as the plate is swung upon its pivot.

In testimony whereof I affix my signature.

WILLIAM H. STORER
